UNITED STATES PATENT OFFICE.

EDWARD J. BRADY, OF CEDAR FALLS, IOWA, ASSIGNOR TO IOWA GATE COMPANY, OF CEDAR FALLS, IOWA, A CORPORATION OF IOWA.

DOUBLE-ACTING STANCHION.

1,264,769.

Specification of Letters Patent. Patented Apr. 30, 1918.

Application filed June 23, 1916. Serial No. 105,379.

To all whom it may concern:

Be it known that I, EDWARD J. BRADY, a citizen of the United States, residing at Cedar Falls, in the county of Blackhawk 5 and State of Iowa, have invented certain new and useful Improvements in Double-Acting Stanchions, of which the following is a production.

My invention belongs to that general class 10 of devices known as stanchions, and particularly cattle stanchions. The invention has among its objects the production of a device of the kind described that is simple, convenient, durable, compact, efficient and 15 satisfactory, for use whenever found applicable. It has particularly as an object the production of a double acting stanchion, that is, one in which the upper ends of the stanchion members are both movable to open 20 the stanchion or close the same. One of the advantages of having double acting stanchions is that stop bars, as they are commonly known, are unnecessary. Other objects and advantages of the construction 25 herein described will appear to those skilled in the art to which the same pertains.

To this end my invention consists in the novel construction, arrangement and combination of parts herein shown and described, 30 and more particularly pointed out in the claims.

In the drawings, wherein like reference characters indicate like or corresponding parts,

35 Figure 1 is a view in elevation of my improved form of stanchion;

Fig. 2 is a sectional view taken substantially on line 2—2 of Fig. 4;

Fig. 3 is a side elevation of a portion of 40 the same, a part broken away to show the construction;

Fig. 4 is a sectional view taken substantially on line 4—4 of Fig. 2;

Fig. 5 is a perspective view of the upper 45 end of one of the stanchion members, and

Fig. 6 is a perspective view of the connecting means between the two stanchion members.

For the purpose of fully illustrating the 50 application and advantages of the construction, I have shown a portion of a stall, consisting of a top bar 1, side members 2 and 3, and curb 4, it being understood that this is merely for illustration, as the stanchion 55 may be used with any style or type of stall

construction. The stanchion consists of the two stanchion members or bars 5 and 6 spaced apart, their ends being preferably brought together at the top and bottom. The lower ends are shown provided with 60 members 7, which are pivotally secured or hinged together at 8, it being understood that any equivalent construction may be employed at the lower end of the stanchion members. The upper ends are preferably 65 provided with members 9 and 10, having extending parts 11 and 12. The extending parts 11 and 12 are arranged within a tubular head or supporting bar 14, which is formed with an opening or slot 15 on the 70 under side, and provided with guides at each side thereof lengthwise the bar. The head bar 14 may be provided with a supporting eye 16, which may be secured to the top part 1 of the stall frame by the link and eye 17, 75 or equivalent means. It will be noted by referring particularly to Figs. 4 and 5, that the extending parts 11 are flanged as at 11', or so as to overlie the guides at each side of the slot 15, the parts being slidable to 80 permit the stanchion members to be moved to either of their two extreme positions, closed and open, as indicated in the full and dotted lines in Fig. 1.

To maintain the stanchion members in 85 closed position, I provide a latch of any suitable form or its equivalent. The latching mechanism shown consists of a latching member 20, pivotally secured at 21 to the part 10, and arranged to engage a lug 19 90 on the part 9. For convenience in controlling or operating the latch, I provide an extending part 22, and if desired, a spring 23, or the equivalent, may be employed for normally maintaining the latch in operative en- 95 gaging position.

Arranged within the head bar 14 is substantially an endless cable 24, which is arranged to run over the sheaves or small pulleys 27 and 28, arranged one at each end 100 of the head bar 14. As shown, the cable or flexible member 24 is crossed between the pulleys 27 and 28, one side being secured to the extension by a fastener 25, or its equivalent, and the other to the part 12 by a 105 fastener 26, or its equivalent, the arrangement being such that as one stanchion member is moved in either direction the other stanchion member is simultaneously moved in the opposite direction. By crossing the 110

cable, as shown, I secure the advantage that the lower runs or sections may be connected to the extensions so that the upper runs or sections are free and away from frictional engagement with said extensions.

In use, assuming that the stanchion is closed as shown in Fig. 1 or 2, and it is desired to open the same to release the stock held thereby. The latch is operated to disengage with the lug 19. Either of the stanchion members may then be moved in a direction to open the same, and this movement is transmitted through the cable to the other stanchion member, moving that in the opposite direction; or in the case of opening one, both are opened. Pushing either one to closed position draws the other stanchion through to closed position, and the latch engaging with the lug 19, automatically locks the parts together. Inasmuch as both of the stanchion bars open, and they lie substantially as indicated by the dotted lines in Fig. 1, stop bars or their equivalents, are unnecessary. It may be said in explanation that where a stanchion opens only on one side, it is customary to extend a bar from the top bar 1 to the curb, or in such position as to prevent cattle passing between the stationary stanchion member and the stall. With the present construction the stanchion, when opened, serves as its own stop, the cattle entering into the space between the stanchion bars. There being no stop bars or the like the cattle are free to turn their heads and have greater movement to the stall, and are thereby afforded greater freedom and comfort, and at the same time the danger of injury to the cattle is obviated.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:—

1. The combination with a pair of stan-

chion members adapted to open and close toward and from each other, said members having extensions at one end thereof, a hollow bar into which said extensions project and longitudinally of which they may slide, and a cable mounted and inclosed within said hollow bar having oppositely movable portions respectively fastened to said extensions at points preventing rubbing engagement of the extensions with the remainder of the cable.

2. The combination with a pair of stanchion members adapted to open and close toward and from each other, said members having extensions at one end thereof, a hollow bar into which said extensions project and longitudinally of which they may slide, and a cable mounted and inclosed within said hollow bar having oppositely movable lower portions respectively fastened to said extensions, said cable being endless and provided with guides at the opposite ends of the hollow bar and crossed centrally of the hollow bar to position the secured extensions of the stanchion members in said central position when said members are closed, substantially as and for the purpose described.

3. The combination with stanchion members connected to open and close toward and from each other, of a hollow approximately straight bar, the stanchion members having extensions projecting into said bar, cable means mounted and inclosed in said hollow bar and having lower sections connected to said extensions to move the stanchion members in opposite directions, the connections between the stanchion members being such that the same will swing in their opening and closing movements, and means for suspending the device in a manner to permit such swinging while permitting the extensions to slide in the hollow bar.

In testimony whereof, I have hereunto signed my name in the presence of two subscribing witnesses.

EDWARD J. BRADY.
